INJECTOR

Hans Deutsch, Vienna, Austria, assignor to the
firm of Alex. Friedmann, Vienna, Austria

Application March 7, 1938, Serial No. 194,457
In Austria January 22, 1938

4 Claims. (Cl. 103—275)

My invention relates to injectors of the kind in which the closure of the overflow valve is automatically controlled by means of a piston. It is necessary in an arrangement of this kind in order to secure immediate restarting of the injector after a sudden interruption of the water-supply, that the mechanism ensuring closure of the overflow valve during the feeding operation of the injector immediately allows free movement of the overflow valve, when the water-supply is momentarily interrupted.

My invention, therefore, provides a multipart piston with stepped parts of different diameter for the control of the overflow valve with two or more parts of different diameter working within a stepped cylinder room. One of said parts is acted upon by the pressure of the live steam admitted to the injector, while another part of said piston is exposed to the pressure which prevails in the delivery chamber or in the delivery pipe of said injector. Whenever the injector fails momentarily on account of an interruption in the water supply, the live steam admitted to the cylinder in which the piston is housed will cause a stroke of the stepped piston and will thus allow free movement of the overflow valve. Conversely the presence of pressure in the delivery chamber of the injector causes a movement of the multipart piston which through an intermediate lever will effectively secure closure of the overflow valve.

A further feature of the invention consists in means for retarding the closure of the overflow valve, when the injector starts feeding. For this purpose a non-return valve is inserted into the pipe leading live or working steam to the stepped cylinder room and opening towards this room. Moreover, one part of the multipart piston is inserted into the corresponding part of the cylinder room with a certain clearance. The fluid mixture in the stepped cylinder by virtue of the non-return valve which prevents its escape towards the admission pipe acts as a brake when pressure is applied to the piston from the delivery chamber on starting as this fluid mixture can only escape very slowly through the clearance between the piston and the surrounding cylinder. Thus, the movement of the piston which on starting and restarting leads to the release of the overflow valve is retarded and the steam filling the overflow chamber before the formation of the jet has sufficient time to escape into the open air. Easy starting and restarting without failure is thus secured.

According to a further modification of the in-

vention the piston consists of three parts of different diameters, with a longitudinal bore in one of said parts and a transversal bore leading into the cylinder room in another part communicating with each other. The longitudinal bore leads to a part of the cylinder connected with the live or working steam admitted to the injector, and this bore is closed by a non-return valve opening towards the transversal bore. The middle part of the cylinder room is connected with the delivery chamber of the injector as already described.

In this modification all the elements necessary for the above described operation are contained within the housing of the multipart piston and the arrangement may therefore be added to an existing injector without modification of the same and without difficulty.

The invention is illustrated in the accompanying drawing which shows several modifications of the same. Figs. 1 and 2 show an injector according to the invention in vertical section and in cross section respectively. Figs. 3, 3a and 4 show two further modifications of the invention. In all figures similar parts are designated by similar reference letters.

In the modification of the injector shown in Figs. 1 and 2, the casing 1 of the injector contains the steam nozzle 2, the combining nozzle 3 and the delivery nozzle 4. By means of the pipe 5 feed-water is supplied to the injector and through the channel 6 and over the check-valve 7 the water to be fed into the boiler is delivered into the pipe 8 leading thereto. A cylinder bore 10 is in connection with the delivery chamber 9 of the injector, which has an extension 11 coaxial therewith, but of smaller diameter. A stepped piston consisting of two parts of different diameter is sliding within the bores 10 and 11. The larger part 12 of the piston is housed in the bore 10, while a smaller rod like part 13 passes through the bore 11 and projects to the outside. Between the part 12 of said piston and the bore 10 a clearance or a small annular space is left so that the mixture of steam and water enclosed within the cylinder room 10 will slowly escape through said clearance if the piston is moved upwardly. The rod like part 13 of the piston is guided in a stuffing box 14. The part projecting to the outside will come into contact with the two-armed lever 15 and 15a which may rock around an axle 16 and which controls the overflow-valve. When the rod like part 13 of the piston presses the end 15 of said lever upwardly, the other end 15a of the lever will come into contact with the valve stem 55

17 of the overflow valve 18 (Fig. 2) and will hold it closed forcibly.

In the position shown in Figs. 1 and 2 the lever 15, 15a however is entirely clear of the overflow valve 18, which is thus released and may freely move. The stepped piston 12, 13 is in this case in its lowermost position as the injector is not working.

From the cylinder room 10 which houses part 10 12 of the piston a channel 19 leads to a chamber 20 which in its turn is connected by means of a channel 20a to a point 20b of the injector to which the live or working steam of the injector is admitted. A ball shaped non-return valve 21 15 is arranged in said chamber 20 which opens in the direction towards the cylinder room 10.

The operation of this arrangement is the following:

When the injector is started the live or working steam under pressure admitted to the injector will also enter at point 20b the channel 20a and will flow through the chamber 20 into the cylinder room 10, so that pressure will be exerted upon the upper surface of part 12 of the stepped piston. The piston is, therefore, pressed downwardly and the overflow valve in this case is released and may freely move as it is no longer held by the lever 15, 15a. The fluid mixture which is formed in the nozzles may thus freely escape to the open air by entering the overflow chamber and passing the overflow valve. As soon as pressure begins to build up in the delivery chamber 9 such pressure is transmitted to the lower surface of the piston part 12 and overcomes the pressure on the upper surface of said part, as the lower surface is larger than the upper surface, the difference in the area being due to the fact that the lower surface is fully utilized while on the upper surface the part 13 of the piston will diminish the exposed area of the surface. Thus, the pressure acting on the upper surface is overcome and the piston 12, 13 is pressed upwardly; the part 13 of the piston will then lift the end 15 of the two-armed lever 15, 15a and will close the overflow valve forcibly.

If, however, the injector fails momentarily, say on account of a sudden interruption of the water supply or from any other cause, the pressure in the delivery chamber 9 is lowered so that it is lower than the pressure of the live or working steam admitted to the injector which prevails in the cylinder room 10 and acts on the upper surface of the piston 12. In this case the multipart piston 12, 13 is moved downwardly, the overflow valve 18 is released and the fluid mixture consisting of steam and water which has entered from the inner parts of the injector into the overflow chamber may escape freely into the open air. When the injector restarts high pressure is again building up in the delivery chamber 9. The stepped multipart piston 12, 13 is therefore again pushed upwardly. The fluid mixture enclosed in the cylinder room 10 above the piston 12 and which is prevented from flowing back by the non-return valve 21 acts as a cushion and is retarding the movement, as it can only escape through the small annular clearance between the piston 12 and the bore of the cylinder room 10 into the delivery chamber 9. The closing of the overflow valve 18 is thereby retarded in such a manner that the steam entering the overflow chamber during the period which is necessary to establish an active jet in the injector has ample time to escape into the open air by means of the overflow valve 18.

In the modification shown in Fig. 3 the stepped multipart piston 12, 13 is directly connected with the delivery check-valve 7 of the injector in such a manner that lifting of the stepped multipart piston at the starting of the injector can only take place simultaneously with the lifting of the pressure valve 7. Likewise the return movements of these two members can only be performed in common. For this purpose the lower face of the piston 12 is provided with a projection or 10 extension 22 which is embraced by a suitably formed part 23 of the valve 7 so that the stepped multipart piston 12, 13 and the valve 7 may only be moved in common. The rest of the arrangement is exactly the same as that described with 15 reference to Figs. 1 and 2. Also the operation of this modification corresponds to that already described with reference to Fig. 1.

In the modification shown in Fig. 3 the piston 12, 13 forms one piece and the delivery check 20 valve 7 is connected with it in the manner described. However, as shown in Fig. 3a also the delivery check valve 7 and the part 12 of the piston might form one piece connected with the part 13 of the piston in the same manner as the delivery check valve 7 is connected with the part 12 of the piston in Fig. 3. The delivery check valve 7 is then provided with a projection carrying a head 24 which constitutes one part of the multipart piston and which is provided with a fork-like extension on top corresponding to part 23 in Fig. 3 and embracing the lower end of the part 13 of the piston corresponding to the extension 22.

In the modification of the invention shown in Fig. 4 the stepped multipart piston 12, 13 which is moving with a certain clearance between it and the cylinder room 28 into the latter is provided with a third part or extension 24 of a smaller diameter than that of the upper rod like part 13 of the stepped piston. This extension 24 40 slides in a bore 25 coaxial with the bore 10 and the stuffing box 14. Thus, a stepped three roomed cylinder houses a piston consisting of three parts of unequal diameter. A small branch of the live or working steam admitted to the injector is conveyed into the cylinder bore 25 by means of the channel or pipe 19 which leads to the cylinder room 25. The extension 24 reciprocating in said room is provided with an axial bore 26 which leads into a transversal bore 27 provided in the part 13 of the piston, a non-return-valve 21 being inserted at the mouth of the bore 26. Thus, the live or working steam admitted to the injector is also admitted to the cylinder bore 10 where it can act on the upper surface of the part 12 of the piston. The cylinder bore 28 which is located below the piston 12 is connected with the delivery chamber 9 of the injector by means of a pipe 29.

All the various other parts are similar to those described and shown with reference to Figs. 1 and 2.

This modification of the invention has the advantage that all parts necessary for controlling the closure and the release of the overflow valve are assembled in the housing of the piston and the arrangement may therefore be very easily added to an existing injector, thus allowing a marked improvement of injectors already in use.

The operation of the modification is the following:

When the injector is started the live steam admitted to the injector flows through pipe 19 and bore 26, lifts the non-return valve 21 and enters into the channel 27 so that the cylinder room 10 above part 12 of the piston is filled with 75

steam under pressure. The piston 12 is in this case pressed downwardly. Thereby the overflow valve will be released. The fluid mixture contained in the overflow chamber may now readily escape into the open air. However, as soon as pressure has built up in the delivery chamber 9 of the injector fluid under pressure will also enter pipe 29 and cylinder chamber 28 located below the piston 12.

10 As the part 13 of the piston is of a larger diameter than the extension 24 at the lower part of the piston the stepped multipart piston 24, 12, 13 moves upwardly and closes the overflow valve 18 and secures closure of said valve during 15 the working of the injector. During such starting or restarting operation of the injector the fluid mixture of steam and water which is enclosed in the cylinder room 10 above the part 12 of the piston and which is prevented from 20 escaping by the non-return valve 21 will act as a retardation means and will slow down the movement of the stepped multipart piston 24, 12, 13. This fluid mixture can only escape through the small annular clearance between 25 the part 12 of the piston and the cylinder room 10 into the cylinder chamber 28. The effect is the same as that described in connection with the modification shown in Figs. 1 and 2. The closing of the overflow valve 18 will thus be retarded so that there is ample time for an efficient feeding jet to build up within the injector. Steam entering into the overflow chamber during this period may escape freely whereby the starting or restarting is greatly facilitated.

35 What I claim is:

1. An injector comprising a delivery chamber, an overflow valve and a seat therefor, a piston with one part exposed to the pressure in the delivery chamber and with another part projecting to the outside, a system of levers acted upon by said outwardly projecting part of the piston and capable of either forcing the overflow valve upon its seat or of allowing free play thereof, said piston being formed as a stepped piston 40 with a large surface acted upon by the pressure of the water delivered from the injector and a small annular surface acted upon by the working steam of the injector, the pressure of the water in the delivery chamber thus acting by means of said piston, its outwardly projecting end and the lever system on the overflow valve of the injector and forcing it upon its seat, while in the absence of pressure in the delivery chamber the pressure of the working steam acting on another surface of the piston will move the same away from the lever system, free play of the overflow valve being thus allowed.

2. An injector comprising a delivery chamber,

an overflow valve and a seat therefor, a piston with one part exposed to the pressure in the delivery chamber of the injector and with another part projecting to the outside, a system of levers acted upon by said outwardly projecting part of the piston, and capable of either forcing the overflow valve upon its seat or of allowing free play of the same, a cylinder, said piston being formed as a stepped piston with a larger portion moving in said cylinder with a certain clearance, and a smaller annular surface acted upon by the working steam of the injector, a pipe leading said working steam to the cylinder and being provided with a check valve opening towards the cylinder.

3. An injector comprising a delivery chamber, an overflow valve and a seat therefor, a piston with one part exposed to the pressure in the delivery chamber of the injector and with another part projecting to the outside, a system of levers acted upon by said outwardly projecting part of the piston and capable of either forcing the overflow valve of the injector upon its seat or of allowing free play of the same, said piston being formed as a stepped piston, with a large surface acted upon by the pressure of the water delivered from the injector and a small annular surface acted upon by the working steam of the injector, the action of said working steam moving the piston away from said lever system and allowing free play of the overflow valve in the absence of pressure in the delivery chamber, a delivery check valve cooperating with said piston whereby the latter moves with the piston.

4. An injector comprising a delivery chamber, an overflow valve and a seat therefor, a piston with one part exposed to the pressure in the delivery chamber of the injector and with another part projecting to the outside, a system of levers, acted upon by said outwardly projecting part of the piston and capable of either forcing the overflow valve of the injector upon its seat or of allowing free play of the same, a cylinder, said piston including cylinders, three stepped parts of different diameter, the first part having the smallest diameter working in one of said cylinders communicating with the working steam chamber of the injector, the second part with the largest diameter moving within another of said cylinders with a certain clearance, the third part projecting to the outside, the first part of the piston having a longitudinal bore and the third part of the piston having a transverse bore communicating with said longitudinal bore and a check valve closing said longitudinal bore.

HANS DEUTSCH.
